UNITED STATES PATENT OFFICE.

VINAL W. SMITH, OF HAVERHILL, MASSACHUSETTS, ASSIGNOR TO SIMPLEX SAMPLE SYSTEM INC., OF HAVERHILL, MASSACHUSETTS, A CORPORATION.

SHOE-DUMMY.

1,160,541.

Specification of Letters Patent.

Patented Nov. 16, 1915.

Application filed June 8, 1915. Serial No. 32,981.

To all whom it may concern:

Be it known that I, VINAL W. SMITH, a citizen of the United States, residing at Haverhill, in the county of Essex and State 5 of Massachusetts, have invented an Improvement in Shoe-Dummies, of which the following is a specification.

This invention relates to certain improvements in shoe-exhibiting devices, or dummies, for illustrating the style, finish, material, and other characteristics of a shoe, in flat form.

Prior to my invention, shoe-upper-sections have been cut out to represent the outline of a shoe, but with this arrangement, the upper was not held in such form as to give a satisfactory idea of the appearance of the shoe, and I have previously mounted the attached upper-sections on a card, but 10 have found this method to be unsatisfactory, as it is difficult to mount the upper so that it will be flat and unwrinkled, and the device is unfinished in appearance.

The object of my present invention is to 25 provide a means for making a shoe dummy in which the attached upper-sections may be supported in flat form, and stretched tightly, so that they will lie flat and smooth, and so as to give a rounding effect at the edge, to 30 give the dummy, more nearly the appearance of a shoe. I accomplish this object by the means shown in the accompanying drawing, in which:—

Figure 1 illustrates a shoe-dummy made 35 according to my invention. Fig. 2 is a sectional view on the line 2—2 of Fig. 1, showing the parts on an enlarged scale. Figs. 3 and 4 are detail views, showing the formation of the edge-portion of the upper and 40 its support, respectively. Fig. 5 is a detail sectional view on the line 5—5 of Fig. 1, showing the parts on an enlarged scale. Fig. 6 is a view of the inner side of the upper support.

According to my invention I provide a 45 stiff card, or mount *a*, similar to an ordinary photographic mount, which will be of suitable size for the purpose. I further provide a flat form *b*, of heavy cardboard, cut out 50 to correspond to the outline, or profile of a shoe. In making the dummy, upper sections *c*, which may be of leather, or cloth, or both, are attached in the form to represent the 55 upper of the shoe, of which the form *b* is a reproduction in profile, each section thereof

being practically a projection of a corresponding part of a shoe upper, and corresponding thereto both in shape and in material, of which it is to be made.

The piece, formed of the connected sections *c*, is made to provide an edge-portion *c'*, which projects a suitable distance beyond the line corresponding to the outline of the form *b*, said piece is placed on the form and stretched tightly thereover, and 60 said edge-portion *c'* is bent about the edge of the form and turned back against the inner side thereof. Before this is done, however, the inner side of the piece is skived, or reduced in thickness, from its edge, to a 65 line which lies within said edge-portion *c'*. The edge-portion of the form *b* is also skived preferably on the side to which the connected sections *c* are applied, although the particular side on which this is done is 70 not a matter of vital importance, as the form is flexible.

After the connected sections *c* have been stretched over the form, the edge-portions *c'* of the sections are turned back beneath the 75 skived portion of the form *b* and secured to the form by cement, and as the material removed by skiving is less than the total thickness of the sections *c*, a continuous surface is provided between the inner side of 80 the support and the surface of the upper. Said form *b*, with the upper sections thereon, is then placed on the mount and held flat thereagainst by an adhesive, the edge-portion of the form being bent slightly so 85 that its side next the mount is flat.

The edge-portion of the form *b* is skived to such a sharp edge and the edge-portion of the upper is skived so thin at the point where it is bent about said edge, that the 90 surface of the upper section practically slopes to the surface of the mount, and a bevel is thus produced at this point, giving a slight rounding effect at the edge, so that the dummy represents a whole shoe, in appearance, somewhat better than if the 95 dummy were absolutely flat throughout.

A strip of leather *d* is secured to the mount against the bottom edge of the form to give the appearance of a sole-edge. 100

If the shoe has a lacing, then the lacing *e* to be represented, will be passed through the eyelets formed in the upper end through both the form and the mount on which it is held, as shown in Figs. 2 and 6, thus show- 110

ing the lacing as it would appear on an actual shoe, and also assisting in attaching the parts together.

I claim:—

5. 1. A shoe-dummy comprising a mount, a flat form shaped to correspond to the outline of a shoe and secured to said mount so that it lies flat thereon except at the edges, and attached sections, representing projections of a shoe upper, stretched over the outer surface of said form, and having edge-portions extending about its edges and turned back onto and secured to its inner side.
10. 2. A shoe-dummy comprising a mount, a flat form shaped to correspond to the outline of a shoe, and secured to said mount, so that it lies flat thereon except at the edges, and attached sections representing projections of a shoe upper, stretched over the outer surface of said form, and having edge-portions extended about its edges, turned back onto its inner side and secured thereto, the edge-portions of said sections and of
20. 25. said form being skived, to provide a continuous flat surface on the inner side of the form extending to its edge.
3. A shoe-dummy comprising a mount, a flat form shaped to correspond to the outline of a shoe, and secured to said mount, so that it lies flat thereon except at the edges, and attached sections, representing projections of a shoe upper, stretched over the outer side of said form and having edge-portions ex-

tended about its edges, turned back onto the inner side thereof, and secured thereto, the edge-portions of said sections and of said form being oppositely skived, and the outer surface of the edge-portion of the form being inclined to the surface of the mount to hold the edge-portion of said sections at a corresponding inclination.

4. A shoe-dummy comprising a mount, a flat form attached thereon and formed to correspond to the profile of a shoe, upper sections drawn closely over said form and about its edge, and connected thereto at its inner side, and a leather strip representing a sole-edge, attached to the surface of the mount and held against the edge of the form.

5. A shoe-dummy comprising a mount, a flat form shaped to correspond to the outline of a shoe and secured to said mount so that it lies flat thereon except at the edges, and attached sections, representing projections of a shoe upper, stretched over the outer surface of said form, and having edge-portions extending about its edge and turned back onto and secured to its inner side, and shoe lacings extending through said sections, form, and mount.

In testimony whereof, I have signed my name to this specification.

VINAL W. SMITH.
